US00D924302S

(12) **United States Design Patent** (10) **Patent No.:** **US D924,302 S**
(45) **Date of Patent:** **** Jul. 6, 2021**

(54) **CAMERA**

(71) Applicant: **SkyBell Technologies, Inc.**, Irvine, CA (US)

(72) Inventors: **Joseph Frank Scalisi**, Yorba Linda, CA (US); **Joon Sung**, Riverside, CA (US)

(73) Assignee: **SkyBell Technologies IP, LLC**, Irvine, CA (US)

(**) Term: **15 Years**

(21) Appl. No.: **29/719,485**

(22) Filed: **Jan. 5, 2020**

(51) LOC (13) Cl. **16-01**

(52) U.S. Cl.

USPC **D16/203**; D16/202

(58) **Field of Classification Search**

USPC D16/200, 202–208, 218, 219; 348/143, 348/148, 151, 373–376; 396/419, 427, 396/535, 539–541

CPC G03B 17/02; G03B 19/04; G03B 17/56; G03B 17/04; G03B 15/03; H04N 5/2251; H04N 5/2252; H04N 5/2253; H04N 5/2254; H04N 7/181; H04N 7/183; H04N 7/18; G08B 13/1963; G08B 13/19619; G08B 13/19632

(57) **CLAIM**

The ornamental design for a camera, as shown and described.

DESCRIPTION

FIG. 1 is a front and first side perspective view of a camera showing our new design;

FIG. 2 is a front, second side, and top perspective view thereof;

FIG. 3 is a front, second side, and bottom perspective view thereof;

FIG. 4 is a front, first side, and top perspective view thereof;

FIG. 5 is a front, second side, and top perspective view thereof;

FIG. 6 is a front view thereof;

FIG. 7 is a back view thereof;

FIG. 8 is a second side view thereof;

FIG. 9 is a first side view thereof;

FIG. 10 is a top view thereof;

FIG. 11 is a bottom view thereof;

FIG. 12 is an exploded front and second side perspective view thereof;

FIG. 13 is an exploded front view thereof; and,

FIG. 14 is an exploded second side view thereof.

The broken lines depict portions of the camera in which the design is embodied that form no part of the claimed design.

1 Claim, 14 Drawing Sheets
